(57) **CLAIM**

The ornamental design for a building controller, as shown and described.

DESCRIPTION

FIG. 1 is a perspective view of a building controller;
 FIG. 2 is a front elevation view of the building controller of FIG. 1;
 FIG. 3 is a right side view of the building controller of FIG. 1;
 FIG. 4 is a left side view of the building controller of FIG. 1;
 FIG. 5 is a bottom side view of the building controller of FIG. 1;
 FIG. 6 is a top side view of the building controller of FIG. 1; and,
 FIG. 7 is a perspective view of the building controller of FIG. 1 with the top and bottom covers removed.
 The portions illustrated in broken lines on the figures are for illustrative purposes only and form no part of the claimed design.
